Primary Examiner — Lauren D McVey*Assistant Examiner* — Sarah L Smith(74) *Attorney, Agent, or Firm* — Olive Law Group, PLLC(57) **CLAIM**

The ornamental design for a fidget toy knife, as shown and described.

DESCRIPTION

FIG. 1 is a top, front, right side perspective view of a fidget toy knife, showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another perspective view of the fidget toy with its knife shown in an extended state.

The broken lines shown in the drawings represent portions of the fidget toy knife that form no part of the claimed design.

1 Claim, 9 Drawing Sheets(56)
